THERMALLY RESPONSIVE SWITCHING DEVICE
 Stanley R. Mitick, Jr., Morrison, Ill., assignor to General
 Electric Company, a corporation of New York
 Filed Jan. 2, 1963, Ser. No. 248,995
 7 Claims. (Cl. 200—138)

This invention relates to thermal switching devices and has particular application to that class of switching devices utilized with warm air furnaces.

Conventional warm air furnace systems generally include a temperature responsive control device, located in the plenum chamber of the furnace, to control the operation of the fan which circulates the warmed air throughout the area to be heated. It is desirable that such a control device should be extremely reliable, while also including a manual adjustment means for varying the control level or point at which the control device can be actuated by a condition responsive element. An important object of the present invention is to provide an improved thermally responsive switching device which is simple and economical in construction, reliable in operation and includes an efficient adjustment means for varying the control level at which the device can be actuated.

It is another object of this invention to provide an improved thermally responsive switching device which includes an accurate and inexpensive adjustment means for varying the control level at which the device can be actuated.

It is a further object of my invention to provide a thermally responsive control device which is of rugged construction and very efficient in operation.

It is a further object of my invention to provide an improved thermally responsive device which includes a manual adjustment means for maintaining the device in the same condition over a prolonged period.

In carrying out one aspect of my invention, in one form thereof, I apply it to a thermally responsive control device for use in a warm air furnace. This device includes a supporting frame, a self-contained switch positioned on one side of the frame, and a bimetal disposed on the other side of the frame. One end of the bimetal is operatively connected with the switch. The other end of the bimetal is carried by one end of a carriage member which is supported on and movable relative to the frame. This carriage member extends on both sides of the frame and it is continuously biased toward the end thereof which carries the bimetal. A cam is rotatably supported on the carriage member at the end thereof opposite the bimetal. This cam is arranged on the carriage member to rotate about an axis transverse to the direction of movement of the carriage member. The cam has a lever arm integral thereto and it is arranged to manually adjust the longitudinal position of the carriage member relative to the frame. Rotation of the cam thus adjusts the position of the bimetal relative to the switch for varying the temperature level at which the switch is actuated by the bimetal. Such an adjustment arrangement for the device is very simplified and economical in construction.

By a further aspect of my invention, I provide an improved arrangement for biasing the carriage member toward the bimetal. This improved arrangement may, of course, be combined with the aforesaid structure to provide a particularly desirable thermally responsive control device. In this arrangement, a tension spring is stretched between a notch formed on the carriage member, and part of the frame, in such a manner that its biasing force pulls the cam toward the frame and also pulls the carriage member into a precise bearing engagement with the frame.

Further aspects of my invention will become apparent hereinafter, and the specification concludes with claims

2

particularly pointing out and distinctly claiming the subject matter which I regard as my invention. The invention, however, as to organization and method of operation, together with further objects and advantages thereof, may best be understood by reference to the following description when taken in conjunction with the accompanying drawings, in which:

FIG. 1 is a side elevational view of a thermally responsive switching device embodying my invention;
 10 FIG. 2 is a left end view of the device shown in FIG. 1;
 FIG. 3 is a side elevational view of the device of FIG. 1, showing the opposite side thereof;
 FIG. 4 is a top view of the device as shown in FIG. 1; and
 15 FIG. 5 is an exploded and fragmentary perspective view of the thermally responsive device.

Referring first to FIGURES 1-4, the temperature control arrangement includes a generally U-shaped channel 10 having side sections 12, 13 (FIG. 2) and connecting portion 14. Each of the side sections 12 and 13 has a pair of spaced apart tongues 16 formed on its upper end (viewing FIGS. 1-3). The tongues 16 on the side sections 12 and 13 are extended upwardly through suitable slots formed in a supporting plate 18, and the sections 12 and 13 are staked to plate 18 as indicated at 20 in FIGS. 1 and 3 to form a rigid supporting frame for the operating mechanism of the device.

To make the desired circuit connections for the control device, a self-contained switch unit 22 has been provided. This switch unit 22 is secured to the supporting frame above plate 18 by placement between opposed pairs of the tongues 16 of the channel 10 (FIG. 4), the extension of screws 24 through aligned apertures of the tongues 16 and the switch housing 32, and the threaded engagement of nuts 26 with the ends 28 of the screws opposite to their heads 30. The threaded ends 28 of the screws 24 are also extended through spacers 31, which are sandwiched by the screws between inner surfaces of associated tongues 16 of the channel, and an adjacent outer surface of the switch housing 32 (FIG. 4).

The switch unit 22 is of the well known self-contained snap acting type, and in the particular illustrated embodiment it includes an insulative box-shaped housing 32 having terminals 34, 36 for the contacts (not shown) extending outwardly from its opposite ends (FIGS. 1-3).
 45 To effect the operation of the contacts of the switch unit 22 between their open and closed positions, as shown in FIGS. 2 and 3, an actuating button 38 is extended outwardly and downwardly through the switch housing 32. The button 38 is normally spring biased to its outermost position by a suitable means within the switch, and when button 38 is in its outermost position the switch contacts are engaged to close a circuit between the terminals 34 and 36.

Turning now to a discussion of the thermally responsive means for actuating the switch unit 22, attention is further directed to FIGS. 2 and 3. On the bottom side of the plate 18 (FIG. 3) and in spaced relation thereto, there is provided a U-shaped bimetal 40. One end 42 of the bimetal 40 is rigidly attached to and supported by the turned over end 44 of an L-shaped carriage member 46. The free end 43 of bimetal 40 is operatively attached to the bottom end 45a of an elongated operating rod 45, the upper end 45b of which (FIG. 2) is normally in operative engagement with the actuating button 38. The stem 48 of the carriage member 46 is guided for sliding movement within generally rectangular slots 49 formed in the supporting plate 18 (FIG. 2), and in a turned over portion 50 (FIG. 5) of a downward extension 52 of side section 13 of the channel 10. To enhance the strength of the carriage member 46 a longitudinal rib 54 is formed in stem 48.

Turning now to an important aspect of the present invention, which concerns a simplified and efficient means for manually setting the control point or response level at which the switch 22 can be actuated by the bimetal 40, attention is directed to FIG. 5. Near the upper end 58 of the slidable carriage member 46, which is disposed between a pair of tongues 16 on one side of the switch housing 32 (FIG. 1), a combination cam and setting lever member 60 is rotatably supported on stem 48. The cam and setting lever member 60 is constructed as a single generally flat piece of metal, and it includes cam section 62, setting arm 63 which extends outwardly in radial fashion from cam section 62, and stop tab 65. The cam section 62 of member 60 is attached to the outer surface of stem 48 of carriage member 46 by extending a shoulder rivet 64 through an aperture of section 62 and an aligned aperture in the stem 48, and then turning over the shanked end of the rivet on the inner surface of stem 48. As shown in FIG. 4, a spring washer 66 is fitted around the shoulder rivet 64 and is in compression between member 60 and stem 48 of carriage member 46. The spaced relationship between the cam section 62 of member 60 and the stem 48, which is provided by the shoulder rivet 64 and spring washer 66, permits the cam section 62 to rotate on the rivet 64 and change its angular relationship with respect to carriage member 46. In addition, the spring 66 exerts a compressive force normal to the head of the rivet 64 to provide a controllable torque which may be suitably maintained for permitting the simplified setting of the cam section 62 to the desired control response.

The cam section 62 of rotatable member 60 is thus positioned on stem 48 of the carriage member 46 for rotative movement about an axis which is perpendicular to the general plane of stem 48 and also perpendicular to the direction of movement of the operating rod 45. To limit the rotative movement of cam and lever member 60, the aforementioned stop tab 65 has an L-shaped configuration (FIG. 4). The turned over end of tab 65 extends through a notch 67 (FIG. 1) cut out of the right edge (FIG. 5) of carriage member stem 48. The angularly spaced side edges 67a and 67b of notch 67 limit the rotation of member 60 to the desired amount, thereby assuring operation within the design range of the control. Directly underneath curved camming edge 62a (FIG. 1) of the cam section 62, there is positioned a calibration screw 68. The screw 68 is arranged in threaded engagement with plate 18, and head 70 of screw 68 is disposed in partially underlying contiguity to camming edge 62a of the member 60. The purpose of such an arrangement, as shall be further understood hereinafter, is to enable camming edge 62a of the lever 60 to rotatably act upon head 70 of the calibration screw 68 to raise or lower carriage member 46 in its guiding slots for setting the desired switch operating temperatures.

To maintain a desired torque on screw 68 and thus control the frictional resistance to its rotation in plate 18, a tension nut 72 is used on the threaded shank of screw 68 between plate 18 and head 70.

To help effectively control the sliding movement of stem 48 of the carriage member 46 in its bearing slots 49, as shown in FIGS. 2 and 5, an elongated tension spring 74 has been provided. The spring 74 is of the helical type, and its hooked ends 74a and 74b, respectively, are secured to an anchor tab 76 formed on extension 52 of channel 10, and a notch 78 formed on the right edge 48a of stem 48 (viewing FIG. 5). The spring 74 is continuously stretched in tension as illustrated in FIGS. 2, 3 and 5, with hooked end 74b secured to the elongated edge 48a of stem 48 furthest away from the edge 52a of channel extension 52 upon which anchor tab 76 is disposed. In addition, from viewing FIGS. 2 and 3 it will be noted that anchor tab 76 is located a considerable distance downwardly from the notch 78. It will thus be noted that, as shown in FIGS. 2 and 3, spring 74 is in effect diagonally wrapped around the inner flat side of stem 48. With such

an arrangement, the tension spring 74 provides a component of force which pulls camming edge 62a into continuous contact with the upper face of the head 70 of the calibration screw 68 and it also provides a force component which pulls stem 48 of the carriage member 46 into contact with the ends 49a (FIG. 5) of the guiding slots 49. In addition, the arrangement of spring 74 also provides the exertion of a twisting force on the stem 48 which causes it to rotate into a fixed relationship with the guiding slots 49. By arranging the tension spring 74 in the aforescribed manner, assurance is provided that the carriage member will always be in the same position under normal operating conditions, and excellent control repeatability is achieved.

As shown in FIG. 4, on the top of insulating base 32 of switch 22, there is attached a suitable temperature scale 80. The scale 80 provides suitable graduations for alignment of the turned over end of setting arm 63 of member 60, to set the desired temperature response for the switch.

Turning now to another aspect of the present invention which concerns itself with a new and improved adjustment means for setting the switch 22 to either "on" or "automatic" operation, attention is directed to FIGS. 3 and 5. As shown therein, my improved control device includes a pivotally mounted lever 90, a pivotally mounted actuator 92 which is manually operated by lever 90, and a spring 94 which is secured to actuator 92 and arranged to maintain it in a normal position. More particularly, the lever 90 is pivotally mounted upon a switch supporting screw 30 located near the right side of the switch (viewing FIG. 3). An annular shoulder spacer 96 (FIG. 2) is sandwiched between the inner surface of lever 90 and an adjacent surface of one of the tongues 16, to permit relatively free pivotal movement of lever 90 between the head of its associated screw 30 and a tongue 16 of the channel 10. As shown in FIGS. 3 and 5, the lever 90 has an L-shaped setting arm 98. Detent notches 100 and 102 are formed in angularly spaced apart relationship on one side of a segment shaped body of the lever 90. The purpose and effect of notches 100 and 102 shall become apparent hereinafter.

As shown in FIG. 5, the actuator 92 is an elongated element which includes a flat body and elongated section 104. An apertured flange 105 is formed upwardly from one of the side edges of section 104 near the right end thereof (viewing FIG. 5), and a lateral tongue 106 extends outwardly from the other side edge of section 104 between its ends. An upwardly curved section 108 is formed on the left end of body section 104 (viewing FIG. 5). The actuator 92 is pivotally mounted upon the switch supporting screw 30 located near the left side of the switch (viewing FIG. 3) by placement of the associated screw 30 through the aforementioned aperture of flange 105. An annular shoulder spacer 110 is sandwiched between the inner surface of flange 105 and an adjacent surface of another tongue 16, to permit relatively free pivotal movement of actuator 92 between the head of its associated screw 30 and a tongue 16 of the channel 10.

As shown in FIGS. 3 and 5, the actuator 92 is pivotally supported upon its associated tongue 16 so that the lateral tongue 106 of the actuator extends over the enlarged head formed on the upper end 45b of operating rod 45, and the curved section 108 of the actuator is engageable by the notches 100 and 102 of the lever 90. The spring 94 is of the elongated leaf type, being suspended in cantilever fashion from the pivotally supported end of actuator 92 (as shown in FIG. 3). A curved nose 94a of the spring 94 engages base plate 18 to impart a biasing force upon the actuator 92, normally urging the lateral tongue 106 upwardly and away from the head of the operating rod 45.

In operation, when the lever 90 is in the position shown in full in FIG. 3 (and also in FIG. 2), the lateral tongue 106 of actuator 92 is spaced apart by a gap and operatively disengaged from the enlarged head of the operating

rod 45. This is referred to as the "automatic" position for the lever 90, since the bimetal 40 is freely capable of operating the button 38 of switch unit 22 in response to temperature variations. The lever 90 is detented or held in this position by the engagement of the curved section 103 of the actuator 92 with notch 102 and the biasing force of spring 94 imparted thereby to the actuator 92 in a counterclockwise direction (viewing FIG. 3).

When the lever 90 is rotated in a counterclockwise direction of rotation from its "automatic" position in FIG. 3 to its dotted position, the curved section 103 of the actuator 92 is cammed by the lever 90 into the detent notch 100, causing the actuator tongue 106 to hold the enlarged head of the operating rod 45 away from the actuating button 38 of the switch unit 22. With the device in this condition, the switch contacts are in their normally closed position to operate the device controlled, such as a fan being used in the summertime, for a continuous period. This position is called the "on" position, since the bimetal 40 is incapable of operating the button of switch unit 22 in response to temperature variations. The lever 90 is detented or held in this position by the engagement of the curved section 103 of the actuator 92 with notch 100. When the lever 90 is in its "on" position the detent notch 100 cooperates with the curved section 103 to provide an effective "self-locking" action which maintains the operating rod 45 in spaced apart relationship to the switch button 38, regardless of the magnitude of force applied to rod 45 by the bimetal 40.

By using the lever 90, actuator 92, and spring 94 in the manner described, a simple and expeditious means is thereby achieved to selectively set the switch unit 22 for "automatic" or "continuous on" type operation.

Turning now to a description of the overall thermally responsive operation of the improved switching device of the present invention, attention is directed to FIGS. 1-4. For normal operation, as illustrated in FIG. 4, setting arm 63 of the rotatable cam and lever member 60 is in a fixed position, and cam section 62 of the member 60 is biased by tension spring 74 into engagement with calibration screw 68. The angular position of cam section 62, which is rotatably supported on carriage member 46, maintains the fixed end 42 of bimetal 40 in a certain spaced relationship with switch actuating button 38. In the illustrated device, as shown in FIG. 1, the high expansion side of the bimetal 40 is disposed on the outside of the U-shaped configuration. As temperature sensed by the bimetal 40 increases, the free end 43 thereof moves away from switch unit 22 (i.e., downwardly viewing FIGS. 1-3), thereby allowing the actuating button 38 to move downwardly to its free position. The normally closed contacts of the switch unit 22 are thereupon snapped to a closed position and a circuit is closed across the terminals 34, 36 to energize a device which is to be controlled, such as a fan motor. As the temperature sensed by the bimetal 40 decreases, the free end 43 of the bimetal moves toward the switch (i.e., upwardly viewing FIGS. 1-3), thereby causing the operating rod 45 to depress (i.e., push up, in FIGS. 2 and 3) the actuating button 38 of the switch unit 22. The upward movement of operating rod 45 thus snaps the normally closed contacts of switch unit 22 to their open position, deenergizing the circuit connected across terminals 34, 36 to turn off the controlled device.

For setting the desired operating temperatures for the controlled device, the setting arm 63 of the combined cam and lever member 60 is rotated to the desired position relative to temperature scale 80. The cam section 62 thereupon acts upon the head 70 of calibration screw 68 to slide the carriage member 46 in its bearing slots 49. The sliding movement of carriage member 46 changes the space relationship between the supported end 42 of bimetal 40 and the switch actuating button 38. This sets the desired level of temperature response for the operation of switch unit 22.

For calibrating the improved control device of the present invention during the manufacture thereof, the setting lever 60 is placed in a predetermined position and, with the bimetal 40 in a liquid bath or some other suitable substance which is at the same temperature indicated on the scale 80, the calibration screw 68 is rotated until the switch operates to its off position.

It will now, therefore, be seen that my new and improved thermally responsive switching device as herein illustrated provides a simple and efficient means for varying the control level at which the device can be actuated. It will also be realized that my improved thermally responsive control device is simple in construction and in overall operation.

15 While in accordance with the Patent Statutes, I have described what at present is considered to be the preferred embodiment of my invention, it will be obvious to those skilled in the art that various changes and modifications may be made therein without departing from my invention, and I, therefore, aim in the following claims to cover all such equivalent variations as fall within the true spirit and scope of this invention.

What I claim as new and desire to secure by Letters Patent of the United States is:

25 1. A temperature responsive device for use in a heating system, said device comprising a support, a switch positioned on said support, an elongated carriage member arranged for sliding movement relative to said support, a bimetal having one end fixed to said carriage member, means operatively connecting the other end of said bimetal with said switch, a first adjustable means for selectively connecting and disconnecting said last mentioned means from said switch, and a second adjustable means supported on said carriage member for manually adjusting the longitudinal position of said carriage member relative to said support, thereby to adjust the position of said bimetal and the temperature level at which said switch is activated by said bimetal.

40 2. The temperature responsive device of claim 1 wherein the first adjustable means includes a rotatable lever and a spring biased actuating element selectively and co-operatively engageable with said lever to operatively connect and disconnect the bimetal from the switch.

45 3. A temperature responsive device for use in a heating system, said device comprising a support, a switch positioned on said support, an elongated carriage member arranged for sliding movement relative to said support, a bimetal having one end fixed to said carriage member, means operatively connecting the other end of said bimetal with said switch, a spring biased actuator mounted for rotation upon said support, a first lever mounted for rotation upon said support, said lever having an angularly spaced apart pair of notches formed therein, the notches of said first lever being arranged to selectively act upon 50 said spring biased actuator for connecting and disconnecting said connecting means from said switch, and a second lever rotatably supported upon said carriage member, said second lever having a cam portion formed therein, said cam portion of said second lever being arranged to act upon said support in response to the angular position of said second lever, thereby to adjust the position of said bimetal and the temperature level at which said switch is actuated by said bimetal.

65 4. A temperature responsive device for use in a heating system, said device comprising a supporting frame, a unitary switch positioned on one side of said frame, a plurality of bearing slots formed in said frame, an elongated carriage member arranged in said bearing slots and extending on both sides of said frame for sliding movement relative thereto, a bimetal having one end fixed to said carriage member on the side of said frame opposite the switch, means operatively connecting the other end of said bimetal with said switch, a cam rotatably supported by said carriage member on the same side of the frame as 70 said switch and being slidable with said carriage member,

said cam being in rotatable engagement with said frame for varying the longitudinal position of said carriage member relative to said frame for adjusting the position of said bimetal, and an elongated spring extending in tension between said carriage member and said frame and disposed on the same side of said frame as said bimetal, said spring means being wrapped around one side of said carriage member and disposed in diagonal relationship to the direction of movement of said carriage member thereby to act upon said carriage member for biasing said 10 slideable carriage member into precise engagement with said bearing means.

5. A temperature responsive device for use in a heating system, said device comprising a support, a switch positioned on said support, a plurality of bearing slots formed on said support, an elongated carriage member in said bearing slots for sliding movement relative to said support, a bimetal having one end fixed to said carriage member, means operatively connecting the other end of said bimetal with said switch, a rotatable cam supported on said carriage member for varying the longitudinal position of said carriage member relative to said support to adjust the position of said bimetal, and an elongated spring extending in tension between said carriage member and said support for operatively engaging said cam with said support, said spring means being wrapped around one side of said carriage member and disposed in diagonal relationship to the direction of movement of said carriage member thereby to bias said cam into engagement with said support and to apply a twisting moment to said carriage member for biasing said slideable carriage member into precise engagement with said bearing slots.

6. A temperature responsive device for use in a heating system, said device comprising a support, a switch positioned on said support, a plurality of bearing slots formed on said support, an elongated carriage member arranged in said bearing slots for sliding movement relative to said support, a bimetal having one end fixed to said carriage member, means operatively connecting the other end of said bimetal with said switch, a spring biased actuator mounted for rotation upon said support, a first lever mounted for rotation upon said support, said lever having an angularly spaced apart pair of notches formed therein, 45 the notches of said first lever being arranged to selectively

act upon said spring biased actuator for connecting and disconnecting said connecting means from said switch, a second lever rotatably supported upon said carriage member, said second lever having a cam portion formed therein, said cam portion of said second lever being arranged to act upon said support in response to the angular position of said second lever, thereby to adjust the position of said bimetal and the temperature level at which said switch is actuated by said bimetal, and an elongated spring extending in tension between said carriage member and said support, said spring being wrapped around one side of said carriage member and disposed in diagonal relationship to the direction of sliding movement of said carriage member thereby to act upon said carriage member for biasing said member into precise engagement with said bearing slots.

7. A temperature responsive device for use in a heating system, said device comprising a support, a switch positioned on said support, an elongated carriage member, bearing means mounting said carriage member on said support for sliding movement relative to said support, a bimetal having one end fixed to said carriage member, means operatively connecting the other end of said bimetal with said switch, adjustable means interengageable between said carriage member and said support for varying the longitudinal position of said carriage member relative to said support for adjusting the position of said bimetal, and an elongated spring extending in tension between said carriage member and said support for operatively engaging the adjustable means between said carriage member and said support, said spring means being wrapped around one side of said carriage member and disposed in diagonal relationship to the direction of movement of said carriage member thereby to apply a twisting moment to said carriage member for biasing said slideable carriage member into precise engagement with said bearing means.
